The ornamental design for a safety mechanism for hypodermic needle, as shown and described.

DESCRIPTION

FIG. 1 is an exploded front top-right side perspective view for a safety mechanism for hypodermic needle, showing my new design in a disassembled configuration;

FIG. 2 is a front elevational view of FIG. 1 thereof;

FIG. 3 is a rear elevational view of FIG. 1 thereof;

FIG. 4 is a left side elevational view of FIG. 1 thereof, the right side elevational view being a mirror image;

FIG. 5 is a front top-right side perspective view of a safety mechanism for hypodermic needle of FIG. 1 thereof, in an assembled configuration;

FIG. 6 is a front elevational view of FIG. 5 thereof;

FIG. 7 is a rear elevational view of FIG. 5 thereof;

FIG. 8 is a left side elevational view of FIG. 5 thereof, the right side elevational view being a mirror image;

FIG. 9 is a top plan view of FIG. 5 thereof;

FIG. 10 is a bottom plan view of FIG. 5 thereof;

FIG. 11 is a front top-right side perspective view of a safety mechanism for hypodermic needle of FIG. 1 with needle syringe thereof, in a disassembled configuration;

FIG. 12 is a front elevational view of FIG. 11 thereof;

FIG. 13 is a rear elevational view of FIG. 11 thereof;

FIG. 14 is a left side elevational view of FIG. 11 thereof, the right side elevational view being a mirror image;

FIG. 15 is a front top-right side perspective view of a safety mechanism for hypodermic needle of FIG. 1 with needle syringe thereof, in an assembled configuration;

FIG. 16 is a front elevational view of FIG. 15 thereof;

FIG. 17 is a rear elevational view of FIG. 15 thereof;

FIG. 18 is a left side elevational view of FIG. 15 thereof, the right side elevational view being a mirror image;

FIG. 19 is a top plan view of FIG. 15 thereof; and,

FIG. 20 is a bottom plan view of FIG. 15 thereof.
